[57] CLAIM

The ornamental design for a crib footboard, as shown and described.

DESCRIPTION

FIG. 1 is a front view of the crib footboard of the present invention;

FIG. 2 is a side view thereof;

FIG. 3 is a top view thereof;

FIG. 4 is a sectional view taken along line 4—4 of FIG. 1;

FIG. 5 is a sectional view taken along line 5—5 of FIG. 1; and

FIG. 6 is a sectional view taken along line 6—6 of FIG. 1.

The rear surface is conventional in appearance.

The crib footboard is characterized by the distinctive configurations and ornamental grooves of the upper cross member adjoining the dowels and the lower cross member adjoining the bottom of the flat panel, as most clearly shown in FIG. 1.
